UNITED STATES PATENT OFFICE

169,388

TABLE

Everett H. Placke, Dayton, Ohio, assignor to The National Cash Register Company, Dayton,
Ohio, a corporation of Maryland

Application November 14, 1952, Serial No. 22,297

Term of patent 14 years

(Cl. D33—14)

To all whom it may concern:

Be it known that I, Everett H. Placke, a citizen of the United States, residing at Dayton, in the county of Montgomery, and State of Ohio, have invented a new, original, and ornamental Design for a Table, of which the following is a specification, reference being had to the accompanying drawings, forming a part hereof, in which:

Fig. 1 is a perspective view of a table showing my new design.

Fig. 2 is another perspective view of a table showing my new design, looking from the reverse side of the showing in Fig. 1.

Fig. 3 is a top plan view of the table.

I claim:

The ornamental design for a table, as shown.
EVERETT H. PLACKE.
